ABSTRACT: A knife control assembly for use in combination with a linecasting machine of the type including a movable knife adjustable to various different slug-trimming positions. The normal linecasting machine includes a pair of coacting screw-type members one of which supports and moves the knife upon rotation of the other. The rotatable screw-type member is normally rotated manually, however, in accordance with the instant invention it includes a gear and is rotated by the control assembly of the instant invention. The assembly of the instant invention includes a motor which rotates this gear through a gear drive train upon receiving a signal from a control means. There is included a multiposition circular switch having a plurality of contacts with each contact corresponding to each of certain selected trimming positions of the knife, and a magnetically closed reed switch and a rotating magnet which closes the reed switch at each of the operative positions of the circular switch. The control means sends a signal to the motor to move the knife to a selected trimming position and when the circular switch reaches a position corresponding to the selected position, the magnet is in the position to close the reed switch thereby sending a signal to the control means to stop the motor, which in turn stops the knife at the precise selected position. The control means includes a register for storing a selected trimming position of the knife, a plurality of electronic gates coupled to the register with the output of each gate being representative of a selected trimming knife position with the outputs of each of said gates being coupled to a contact of the circular switch.

**AUTOMATIC KNIFE BLOCK CONTROL ASSEMBLY FOR
A LINECASTING MACHINE**

The instant invention relates to an improved automatic knife block control assembly for a linecasting machine. Although the invention will be described and illustrated in an Intertype linecasting machine it will be understood by those skilled in the art that it is also applicable to other line casting machines.

As is well known by those skilled in the art, an Intertype linecasting machine includes a plurality of magazines which are selectively placed in an operative position for supplying matrices of particular fonts. Each font has a recess defining a mold for a particular alphanumeric character. When a particular magazine is in the operative position, the fonts are supplied to a casting position where the fonts are disposed one beside another and are placed in position adjacent a mold cavity so that hot metal disposed in the mold cavity is impressed with the fonts to form a slug which in turn is used to define a line of print in a column of printed matter such as that in a newspaper. The mold disc has several molding cavities and each cavity is useful for casting a different size of font. When a certain mold cavity is being utilized it is in the operative position and is rotated between a casting position and an ejecting position where the slug (the piece of metal having the letters molded on one face thereof) is ejected through a knife block where it is sized by severing or cutting the metal from its opposite sides.

In the Intertype linecasting machine, the knife block normally includes a stationary knife and a movable knife which is rectilinearly movable toward and away from the stationary knife so that the distance between the knives changes for sizing slugs having different distances between the sides. The reason for the differences in distance between the sides is because of the different sizes of letters molded on the slugs, *i.e.*, the different sizes of fonts utilized in the casting step. In the basic Intertype machine the position of the movable knife is determined by an indexing assembly having dials and including a member which is manually rotatable to a selected position to move the movable knife to the approximate desired position. One of the problems with this assembly is, of course, the level of accuracy obtainable in manually positioning the movable knife. In other words, the tolerances to which the movable knife may be positioned by manually indexing such an assembly are indeed not very precise.

Recently there have been developments wherein the movement of the movable knife is automated. The problem with such mechanisms is one of not having the capability of moving the movable knife to a position within the desired tolerances. In other words, such assemblies are not capable of moving the knife to a position of the desired preciseness. The reason for this is exemplified in a prior art mechanism which includes a plurality of mechanical stop members which coact and engage one another to control the position of the movable knife member. Such mechanical stops do not provide the desired preciseness in positioning the movable knife.

Accordingly, it is an object and feature of this invention to provide an improved automatic knife block control assembly adapted to move the movable knife to a position which is within closer tolerances of the desired position than heretofore unobtainable.

In correlation with the foregoing object and feature, it is an object and feature of this invention to provide a knife control assembly including actuation means for moving the knife between trimming positions with coarse sensing means for providing a signal when the knife approaches the selected trimming position and a fine sensing means for providing a signal when the knife reaches the selected trimming position to deactivate the actuation means whereby the knife stops moving at a position which is within closer tolerances to the desired position than heretofore obtainable.

In correlation with the foregoing objects and features, another object and feature of this invention is to provide a

switch with each operative position thereof corresponding to a selected trimming position of the knife and wherein the fine sensing means includes a magnetically closed reed switch and a rotating magnet which closes the reed switch as the circular switch reaches each position thereof.

In correlation with the foregoing objects and features, another object and feature of this invention is to provide an actuating means which includes a motor and control means which reverses the motor as the movable knife reaches each extreme position of movement for stopping the motor means only when the movable knife reaches the selected trimming position during movement of the knife from the extreme fully opened position toward the fully closed position; thus, reducing backlash in the mechanical drive means of the actuation means so that the knife may be positioned within the tolerances desired.

Another object and feature of this invention is to provide means whereby the knife can be set automatically and also by manual switching means.

10 In correlation with the foregoing objects and features, a control means is provided including a register adapted to be set by manual switching means and also by signals received from a decoding means.

15 Other objects and attendant advantages of the present invention will be readily appreciated as the same becomes better understood by reference to the following detailed description when considered in connection with the accompanying drawings wherein:

20 FIG. 1 is a fragmentary plan view showing a preferred embodiment of a knife control assembly and a portion of a linecasting machine assembly;

25 FIG. 2 is a view taken substantially along line 2-2 of FIG. 1;
FIG. 3 is a fragmentary cross-sectional view of a portion of

30 the assembly;

35 FIG. 4 is a cross-sectional view taken substantially along line 4-4 of FIG. 1;

40 FIG. 5 is a cross-sectional view taken substantially along line 5-5 of FIG. 4;

45 FIG. 6 is a schematic of the control means of the preferred embodiment of the invention;

50 FIG. 7 is a schematic of the motor control means of the preferred embodiment of the invention; and

55 FIG. 8 is a schematic of the extreme position-sensing means of the invention.

Constructive details of the linecasting machines are well known to those skilled in the art and will not be set forth in detail herein except as necessary. Reference may be had to a manual published by the Intertype Corporation, copyright 1943, and entitled "The Intertype" for a specific description of an Intertype line casting machine with which the instant invention may be utilized. Reference may also be had to the official manual of the Mergenthaler Linotype Company, Brooklyn, N.Y., copyright 1940, and entitled "Linotype Machine Principles" for an understanding and more specific description of a Linotype machine of the type with which the instant invention may be utilized.

Referring now to the drawings wherein like numerals indicate like or corresponding parts throughout the several views, a knife control assembly is shown in combination with a portion of an Intertype linecasting machine generally at 10.

The linecasting machine includes a stationary knife 12 and a movable knife 14. The movable knife 14 is movable rectilinearly toward and away from the stationary knife 12 between a fully open position and a fully closed position. The space between the knives 12 and 14 determines the thickness of the distance between the sides of the slugs being trimmed. The circular member 16 is a stationary part of the linecasting

70 machine and is a screw member which coacts with another screw member 18. The screw member 18 supports the movable knife 14 and moves the knife 14 toward and away from the stationary knife 12. In other words, the screw members 16 and 18 coact together through the screw threads 20 and rotation 75 of the screw member 18 causes it to move axially thereby

moving the movable knife 14 rectilinearly toward and away from the stationary knife 12.

The knife control assembly includes a support plate 22 which is clamped about the screw member 16 and firmly held thereto by a bolt 24. Other brackets (not shown) may also be utilized to secure the support plate 22 on the linecasting machine.

The knife control assembly includes actuation means generally shown at 26 for moving the knife 14 between trimming positions. The knife control assembly also includes course sensing means generally indicated at 28 for providing a signal when the knife 14 is nearer to the selected trimming position than any other trimming position. That is to say, the knife 14 may be moved to any one of various different selected trimming positions all of which are at a different distance from the stationary knife 12. When the knife 14 is very close to the desired or selected trimming position, the course sensing means provides a signal indicating that the knife is approaching the selected trimming position. The knife control assembly also includes a fine sensing means, which is generally indicated at 30 in FIG. 3, for providing a signal when the knife 14 reaches the selected trimming position to deactivate the actuation means 26 whereby the knife 14 stops moving.

The course sensing means 28 includes a plurality of predetermined spaced positions which correspond generally to the respective trimming positions of the knife 14 so that the course sensing means 28 provides a signal when the knife 14 is very nearly in the selected trimming position. More specifically, the course sensing means 28 is a multiposition circular switch with each operative position of the switch corresponding to a trimming position. The switch may be one having a plurality of contacts disposed in a circle with a rotary arm moving from one contact to the other and with each contact corresponding to a trimming position of the knife 14. It will be appreciated that as the arm moves into engagement with a given contact to establish electrical current flow, the knife 14 is not quite at the precise desired selected trimming position.

The fine sensing means 30 includes a magnetically closed reed switch 32 and a rotating magnet 34 which closes the reed switch 32 at each position of the circular switch of the course sensing means 28. In other words, the gearing, as will be explained more fully hereinafter, is such that the magnet 34 is moved into position for closing the reed switch 32 each time the arm of the circular switch engages a different contact. The closing of the reed switch 32, however, does not provide a signal which stops the actuating means 26, thereby stopping the knife 14 in the precise desired position, unless the circular switch is in the position corresponding to the selected trimming position.

The actuation means 26 includes a reversible motor means 36 for moving the movable knife 14 between the open and closed positions, and in the preferred embodiment is a 72 pole slo-syn motor which is shown schematically in FIG. 7. There is also included a control means as shown in FIGS. 6 through 8 to reverse the motor means 36 when the knife 14 reaches each of the fully open and fully closed positions and for stopping the motor means only when the movable knife 14 reaches the selected trimming position during movement thereof from the fully open position toward the fully closed position. In other words, the desired selected trimming position of the knife 14 is only reached as the movable knife 14 is moving toward the stationary knife 12. The means to accomplish this will become more clear when the control means 38 is described more fully hereinafter. The purpose for this function, however, is to eliminate backlash in the gearing of the system, both the gearing of the linecasting machine and the gearing of the knife control assembly.

The screw member 18 has a first gear 40 secured thereto by the bolts 42. The actuation means also includes a gear train for transmitting motion between the motor means 36 and the first gear 40. That gear train includes the bevel gears 44 and 46, the spur gears, 48, 50 and 52, the latter gear being in meshing engagement with the first gear 40.

The course sensing means 28 also includes a first drive means for rotating the circular switch in response to rotation of the rotating screw member 18. This first drive means includes the shaft 54, which is rotated by the spur gears 56 and 58, the latter gear being in driving engagement with the gear 50 because of a pin 60.

The fine sensing means 30 includes a second drive means for rotating the magnet 34 in response to rotation of the rotating screw member 18 (i.e., in response to movement of the knife 14). The second drive means includes the gears 62, 64, 66 and 68. A shaft 70 is rotatably supported in the bearings 72. The gear 52 is nonrotatably secured thereto by the pin 74, the gears 50 and 58, as previously mentioned being secured thereto by the pin 60, and the gear 68 being secured thereto by the pin 76.

The component 78 includes the circular switch but is actually a double-deck switch. One deck defines the circular switch and the other deck is a component of the control means and has two positions, one position to indicate when the knife 14 is fully closed and one position to indicate when the knife 14 is fully open. This deck of component 78 is shown schematically with reference to FIG. 8. Hence, a signal is provided for reversing the direction of rotation of the motor means 36 when the knife reaches the extreme positions of movement.

25 The component 78 includes a look-through, clear face 80 behind which is disposed a disc 82 with indices thereon. The indices, as best illustrated in FIG. 2, are marked off from 4 to 36. The indices 4 to 36 indicate the number of points. A point is a measure of thickness of the slug which, in turn, is a function of

30 the height of the letters on a printed page. Each point equals fourteen-thousandths (0.014) of an inch. In the devices illustrated, the knife may be positioned at any selected trimming position which is at an equal number of points between and including 4 and 36 points, i.e., 4, 6, 8, 10, etc. When a signal is provided to position the knife 14 at a selected trimming position, which is defined by a certain even number of points, the motor means 36 rotates to rotate the screw member 18 which in turn moves the knife 14. If the knife 14 is initially at the 10-point position and the signal is to position the knife 14 at the

40 20-point position, the motor rotates in the direction to move the knife 14 toward the stationary knife 12. When the knife 14 reaches the fully closed position the other switch is activated to provide a signal which is utilized to reverse the direction of rotation of the motor 36 so that the knife 14 moves away from the stationary knife 12. The knife 14 then moves away from the stationary knife 12 until it reaches the fully open position, i.e., it does not stop at the desired position of 10 points. When the knife 14 reaches the fully open position, the switch forming a second deck of the component 78 provides another

50 signal which again reverses the direction of rotation of the motor means 36 to move the knife 14 toward the stationary knife 12 until the arm in the circular switch engages the contact corresponding to the 10-point position. Current is then sent through the circular switch. However, the circular switch

55 is in series with the reed switch 32. The drive gears 62, 64, 66 and 68 however move the magnet 34 into position relative to the reed switch 32 so as to close the reed switch 32 when the knife 14 is at or within the desired tolerances of the selected trimming position. By utilizing the course and fine sensing means respectively, the knife 14 may be moved to within one-thousandth (0.001) of an inch of the exact precise position. In other words, the knife control assembly of the instant invention may move a knife within one-thousandth (0.001) of an inch in tolerance. Furthermore, as alluded to above, the system only reaches the selected trimming position when the knife 14 is moving toward the stationary knife 12, thus eliminating backlash in the mechanical drive systems and further allowing the knife to be positioned within one-thousandth (0.001) of an inch in tolerance.

60 70 There is also included a manually actuable drive means comprising the knurled wheel 84 for rotating the gears 48, 50, 52 and 40 to move the knife 14. The indicator face or dial 82, therefore, provides an indicator means for indicating the position of the knife and is particularly useful when the position thereof is manually adjusted by rotating the wheel 84.

Now to more specifically describe the control means 38, and with particular reference to FIGS. 6 through 8 it should first be noted that the control means 38 is designed to operate in conjunction with the auxiliary function control means disclosed in copending U.S. Pat. application Ser. No. 717,328, filed Mar. 29, 1968 entitled "Automatic Saw Control Assembly for a Linecasting Machine" filed simultaneously with this application and which is assigned to the assignee of this application. However, it should be understood that any means for electronically or otherwise developing a signal representative of the various positions of movable knife 14 may be employed with the invention herein disclosed.

The system of the aforesaid U.S. Pat. application Ser. No. 717,328 utilizes a means for applying numbers in the standard teletype code along with coded letters representing auxiliary linecasting machine functions such as the knife block (K), the saw (S), and mold disc (D) to the decoder. The output of the decoder represents digits in the 8-4-2-1 BCD code and also has outputs for each auxiliary function such as K, S and D and their inverses. Such outputs are used by control means 38 as hereinafter described.

Turning now to FIGS. 6 through 8, there is schematically shown control means 38 for controlling either automatically or semiautomatically the position of knife 14 in response to the movement of gear 40. The new selected or command position for the knife is placed in a command position register 100 either from the decoder of the aforesaid application or semiautomatically by manual switching means (not shown). Register 100 consists of four flip-flops 102, 104, 106 and 108. Each flip-flop is preferably formed from a pair of NAND gates arranged in the well-known manner and has set and reset input lines, and 0 and 1 output lines in the well-known conventional manner. The register 100 is designed to store a decimal digit in the 8-4-2-1 BCD code with flip-flop 102 storing the ones digit, flip-flop 104 storing the twos digit, flip-flop 106 storing the fours digit, and flip-flop 108 storing the eights digit. The set line for flip-flop 102 is connected by means of line 110 to a semiautomatic switching means, generally an electronic decade switching means (not shown), and lines 112, 114 and 116 are similarly connected with respect to flip-flops 104, 106 and 108 respectively. Lines 110, 112, 114 and 116 enable the register 100 to be set semiautomatically by an operator operating the switching means. The set line of flip-flops 102, 104, 106 and 108 are also connected to the outputs of NAND gates 118, 120, 122 and 124 respectively. One input line of gates 118, 120, 122 and 124 respectively are the 1, 2, 4 and 8 lines respectively from the decoder of the aforesaid application. The common input to gates 118, 120, 122 and 124 is the 1 output from control flip-flop 126. Flip-flop 126 has its set line connected to the $\bar{K}$ line from the decoder of the aforesaid application and consequently is generally maintained in the reset state, being set by a signal appearing on the $\bar{K}$ line. The reset line of flip-flop 126 is connected through inverter 128 to NAND gate 130 whose inputs are the inverses of the other auxiliary function lines. As is apparent, only when flip-flop 126 is in the set state will gates 118, 120, 122 and 124 let information carried on lines 1, 2, 4 and 8 pass to register 100.

The output from flip-flops 102, 104, 106 and 108 are connected to a means for converting numbers in the 8-4-2-1 BCD code to decimal digits and is formed by coupling NAND gates 132, 134, 136, 138, 140, 142, 144, 146 and 148 to the outputs of flip-flops 102, 104, 106 and 108. Gate 132 has its inputs connected to the 1 output of flip-flop 102 and the 0 outputs of flip-flops 104, 106 and 108. Gate 134 has as its inputs the 0 outputs of flip-flops 102, 106 and 108 and the 1 output of flip-flop 104. Gate 136 has as its inputs the 1 output of flip-flops 102 and 104 and the 0 output of flip-flops 106 and 108. Gate 138 has as its inputs the 0 outputs of flip-flops 102, 104 and 108 and the 1 output of 106. Gate 140 has as its inputs the 1 output of flip-flops 102 and 106 and the 0 output of 104 and 108. Gate 142 has as its inputs the 1 output of flip-flops 104 and 106 and the 0 output of 102 and 108. Gate

106 and the 0 output of 108. Gate 146 has as its inputs the 1 output of flip-flop 108 and the 0 output of 102, 104 and 106. Gate 148 has as its inputs the 1 output of flip-flops 102 and 108 and the 0 outputs of 104 and 106. As is readily apparent, the outputs of gates 132, 134, 136, 138, 140, 142, 144, 146 and 148 represent 9 knife positions, 1, 2, 3, 4, 5, 6, 7, 8 and 9 respectively. When one of the latter positions is stored in BCD form in register 100, the output of its corresponding NAND gate is at ground, with all other NAND gate outputs being positive.

In order to activate the system in response to information being placed in register 100, NAND gate 150 is utilized having as inputs the 0 outputs of each of flip-flops 102, 104, 106 and 108. The output of gate 150 is applied to the base of NPN transistor 152 whose emitter is grounded and whose collector is coupled to a 24-volt source through the energizing circuit of normally open relay 152. The base of transistor 154 is also coupled to a 5-volt source so that in the absence of any number being stored in register 100 the output of gate 150 is grounded biasing transistor 152 off so that relay 154 hereinafter described is open. However, when a number is stored in register 100, transistor 152 is turned on and relay 154 is thus closed.

A 24-volt source is connected through relay 154 and relay energizing circuit 156 to ground. When relay 156, as shall hereinafter be described with reference to FIG. 7 is closed, motor means 36 is turned on. With particular reference to FIG. 7, slo-syn motor means 36 is shown schematically having a pair of windings 158 and 160 with one terminal of each of windings 158 and 160 being coupled together through resistor 174 and capacitor 176. Winding 158 is connected from one terminal of a 110-volt-AC source, triac 168, and normally open relay 156 to the other source terminal. The gate of triac 168 is coupled through normally open latching relay 162, resistor 170 and winding 158 to a terminal of the AC source. Winding 160 is connected from one terminal of a 110-volt-AC source, triac 166 and normally open relay 156 to a terminal of a 110-volt-AC source. The gate of triac 166 is coupled through normally closed latching relay 162, resistor 172 and winding 160 to a terminal of the source. As is apparent, when relay 156 is closed, either triac 166 or 168 conducts depending on the state of the energizing circuit of relay 162 to be hereinafter described. Thus, the motor 36 is driven in one of two directions when relay 156 is closed depending on relay 162.

Now with reference to the extreme position sensing means of FIG. 8, relay 162 is controlled by a second arm 164 of the component 78. This arm is designed to indicate when the knife is in either of the two extreme positions. When the arm as shown by the broken line of FIG. 8 indicates that knife 14 is in the fully closed position, a 24-volt potential is applied across the latching coil 162L of relay 162 whereby the normally closed relay contacts 162 are latched open and the normally open contacts are latched closed. In contrast, when arm 164 as shown in FIG. 8 indicates that the knife 14 is in the fully open position, it applies a 24-volt potential across the unlatching coil 162U of relay 162 whereby the normally closed relay contacts 162 previously opened by coil 162L are closed and the normally open latch relay contacts 162 previously closed by coil 162L are opened. Thus, the latching and unlatching coils 162L and 162U as shown in FIG. 8 control which of triacs 166 and 168 are open and hence which one of windings 158 and 168 is energized.

In order to stop motor 36 when knife 14 has reached the indicated position, the arm of component 78 shown schematically as 166 of FIG. 6 as it sweeps the outputs of gates 132, 134, 136, 138, 140, 142, 144, 146 and 148 is connected in series with reed switch 32, normally closed relay 162 and reset line 178, the latter being coupled to the reset inputs of flip-flops 102, 104, 106, 108 and 126. When arm 166 senses that the output of one of the NAND gates 132, 134, 136, 138, 140, 142, 144, 146 and 148 is at ground and also when the

relay 162 is latched closed, then and only then will the flip-flops of register 100 be reset opening relay 154 thus turning off the system. Since relay 162 will be open only when the knife is moving toward its closed position, as has been previously explained, backlash is generally eliminated since the system will be shut off only when a ground potential is sensed by arm 166 as knife 14 moves toward its fully closed position. Placing line 178 at ground will, as has been mentioned, reset flip-flop 126 if flip-flop 126 has not been reset by the receipt of another auxiliary function signal at gate 130. Once, however, register 100 is reset the system is stable and is able to receive a new knife command position either by signals from the encoder or by signals applied by manual switching means along lines 110, 112, 114 and 116.

We claim:

1. A knife control assembly for use in combination with a linecasting machine of the type including a movable knife adjustable to various different slug-trimming positions, said assembly comprising, actuation means for moving the knife between the trimming positions, course sensing means for providing a signal when the knife is nearer to a selected trimming position than any other trimming position, and fine sensing means activated by said signal for providing a stop signal when the knife reaches the selected trimming position to deactivate said actuation means whereby the knife stops moving.

2. An assembly as set forth in claim 1 wherein said course sensing means includes a plurality of predetermined spaced positions which correspond generally to the respective trimming positions of the knife so that said course sensing means provides said signal therefrom when the knife is very nearly in the selected trimming position.

3. An assembly as set forth in claim 2 wherein said course sensing means is a multiposition circular switch with each operative position corresponding to a selected trimming position.

4. An assembly as set forth in claim 3 wherein said fine sensing means includes a magnetically closed reed switch and a rotating magnet which closes said reed switch at each position of said circular switch.

5. An assembly as set forth in claim 2 wherein said actuation means includes motor means adapted for moving the movable knife between fully open and fully closed positions.

6. An assembly as set forth in claim 5 wherein said motor means is reversible, and including control means adapted to reverse said motor means when the movable knife reaches said positions and for stopping said motor means only when the movable knife reaches the selected trimming position during movement thereof from said fully open position toward said fully closed position.

7. An assembly as set forth in claim 6 wherein said course sensing means is a multiposition circular switch with each operative position thereof corresponding to a selected trimming position.

8. An assembly as set forth in claim 7 wherein said course sensing means includes first drive means adapted for rotating said circular switch in response to movement of the knife.

9. An assembly as set forth in claim 8 wherein said fine sensing means includes a magnetically closed reed switch and a rotating magnet which closes said reed switch upon each revolution thereof.

10. An assembly as set forth in claim 9 wherein said fine sensing means includes second drive means adapted for rotating said magnet in response to movement of the knife so that said magnet is in position to close said reed switch at each position of said circular switch.

11. An assembly as set forth in claim 2 including a stationary knife, said movable knife being rectilinearly movable toward and away from said stationary knife between a fully open position and a fully closed position, and wherein said actuation means includes motor means for moving said movable

12. An assembly as set forth in claim 11 wherein said motor means is reversible, and including control means to reverse said motor means when said movable knife reaches said positions and for stopping said motor means only when said movable knife reaches the selected trimming position during movement thereof from said fully open position toward said fully closed position.

13. An assembly as set forth in claim 12 including a pair of coacting screw members one of which supports and moves said movable knife upon rotation of the other, the latter including a first gear, and wherein said actuation means includes a gear train for transmitting motion between said motor means and said first gear.

14. An assembly as set forth in claim 13 wherein said course sensing means is a multiposition circular switch with each operative position thereof corresponding to a selected trimming position.

15. An assembly as set forth in claim 14 wherein said course sensing means includes first drive means for rotating said circular switch in response to rotation of the rotating screw member.

16. An assembly as set forth in claim 15 wherein said fine sensing means includes a magnetically closed reed switch and a rotating magnet which closes said reed switch upon each revolution thereof.

17. An assembly as set forth in claim 16 wherein said fine sensing means includes second drive means for rotating said magnet in response to rotation of said rotating screw member so that said magnet is in position to close said reed switch at each position of said circular switch.

18. An assembly as set forth in claim 17 including manually actuatable drive means for moving the knife, and indicator means for indicating the position of the knife.

19. A linecasting machine assembly including a movable knife adjustable to different slug-trimming positions and a knife control assembly comprising actuation means for moving said knife between said trimming positions, a register adapted for storing a selected trimming position of said knife, a plurality of electronic gates coupled to said register, the output of each of said gates being representative of a selected trimming knife position, means cooperating with said outputs of said gates for providing a signal when said knife is nearer to a selected trimming position than any other trimming position, and fine sensing means activated by said signal for providing a stop signal when said knife reaches the selected trimming position to deactivate said actuation means whereby said knife stops moving.

20. An assembly as set forth in claim 19 wherein said register is adapted to be set by both manual switching means and by signals received from a decoder following the receipt of a knife control signal.

21. An assembly as set forth in claim 19 wherein means cooperating with said outputs of said gates includes a multiposition circular switch having an arm and a plurality of contacts, each of said gates having its output coupled to a different one of said contacts and wherein said arm sweeps said contacts when said actuation means is actuated.

22. An assembly as set forth in claim 21 wherein said actuation means includes motor means and additionally including extreme position means for electrically indicating a fully open signal and a fully closed signal when said knife reaches its fully open and fully closed positions respectively and further wherein said actuation means includes reversible motor means, said motor means reversing upon receipt of said fully open or fully closed signal, means for maintaining said fully open signal until a fully closed signal is received and means for maintaining said fully closed signal until said fully open signal is received.

23. An assembly as set forth in claim 22 wherein said motor means is deactivated upon the simultaneous receipt of said signal indicating that said knife is nearer to a selected trimming position than any other trimming position, said stop

has reached the selected trimming position, and said fully opened signal.

24. An assembly as set forth in claim 23 wherein there is provided means for actuating said motor means by a signal indicating that a number is stored in said register, and means for deactivating said motor means when said register is reset.

25. An assembly as set forth in claim 24 wherein said motor means is a slo-syn motor having a pair of windings, one winding being activated upon receipt of a fully closed position signal and the other winding being activated by said fully open

signal for reversing the direction of said motor means.

26. An assembly as set forth in claim 25 wherein said fine sensing means includes a magnetically closed reed switch and a rotating magnet which closes said reed switch at each contact of said multiposition switch.

27. An assembly as set forth in claim 26 wherein said arm is electrically coupled to reset said register through said reed switch only upon receipt of said fully open signal.
